[57] **CLAIM**

The ornamental design for a leg for a display rack, as shown and described.

DESCRIPTION

FIG. 1 is a perspective view from one end, the top, and one side of the leg for a display rack;

FIG. 2 is a perspective view from the opposite end of FIG. 1 also showing the top and the other side;

FIG. 3 is an end elevational view from the FIG. 1 end;

FIG. 4 is an end elevational view from the FIG. 2 end;

FIG. 5 is a side elevational view of one side, the other side being a mirror image thereof; and,

FIG. 6 is a top plan view thereof, the bottom being a mirror image thereof.
